DESIGN.

W. BLACKBURN.
CARPET.

No. 20,259.

Patented Nov. 4, 1890.

UNITED STATES PATENT OFFICE.

WALTER BLACKBURN, OF YONKERS, NEW YORK, ASSIGNOR TO THE ALEX.
SMITH & SONS CARPET COMPANY, OF SAME PLACE.

DESIGN FOR A CARPET.

SPECIFICATION forming part of Design No. 20,259, dated November 4, 1890.

Application filed October 10, 1890. Serial No. 367,641. Term of patent 3½ years.

To all whom it may concern:

Be it known that I, WALTER BLACKBURN, a citizen of the United States, residing at Yonkers, Westchester county, State of New York, have invented a new and original Design for Carpets, of which the following is a specification, reference being had to the accompanying photograph, which forms a part of the same.

10 The invention relates to a design to be worked into or upon surfaces, such as carpets or similar fabrics; and it consists in the novel configuration and grouping of figures herein specifically shown and claimed.

The accompanying photograph is a face 15 view of a carpet showing my new design.

My design consists of sprays or groups of conventionalized leaf and flower forms on curving stems or branches and lying on a shaded ground.

What I claim as new, and desire to secure by Letters Patent, is—

The design for a carpet, consisting of the design substantially as shown.

WALTER BLACKBURN.
